UNITED STATES PATENT OFFICE.

HENRY FLEETWOOD ALBRIGHT, OF OAK PARK, ILLINOIS, ASSIGNOR TO WESTERN ELECTRIC COMPANY, INCORPORATED, OF NEW YORK, N. Y., A CORPORATION OF NEW YORK.

GRINDING, POLISHING, AND BUFFING MACHINE AND THE LIKE.

1,339,312.

Specification of Letters Patent.

Patented May 4, 1920.

Application filed October 27, 1918. Serial No. 128,039.

To all whom it may concern:

Be it known that I, HENRY FLEETWOOD ALBRIGHT, a citizen of the United States, residing at Oak Park, in the county of Cook and State of Illinois, have invented certain new and useful Improvements in Grinding, Polishing, and Buffing Machines and the like, of which the following is a full, clear, concise, and exact description.

10 This invention relates to improvements in grinding, polishing, and buffing machines, and the like.

One of the objects of the invention is to provide improved means whereby abrading 15 wheels of various diameters may be interchangeably employed without exceeding a safe peripheral speed.

Another object is to provide means for 20 manually adjusting the speed of the motor through a rheostat in conjunction with indicating means for indicating to the operator the desired speed for abrading wheels of any diameter.

In the accompanying drawings in which a 25 practical embodiment of the invention is illustrated:

Figure 1 is a side elevation of the driving motor and controlling rheostat;

Fig. 2 is a section on the line 2—2 of 30 Fig. 1;

Fig. 3 is a central sectional elevation of the motor frame, certain parts being omitted for the sake of clearness;

Fig. 4 is a side elevation of a pair of 35 polishing and buffing wheels and a housing therefor;

Fig. 5 is a section on the line 5—5 of Fig. 4;

Fig. 6 is a top plan view of the polishing 40 and buffing apparatus shown in Fig. 4, and

Fig. 7 is a front elevation of a complete duplex polishing and buffing equipment.

The polishing and buffing wheels are 45 driven by a suitable motor 1 on the armature shaft 2 of which the abrading wheels 3, 4 may be directly mounted. Said wheels may be grinding, buffing, or polishing wheels, or any other type of abrading wheels. Said wheels are mounted prefer- 50 ably in pairs, there being two sets on each end of said shaft, as shown in Fig. 7. Said wheels are removably mounted whereby they may be removed and other wheels substituted therefor.

Each pair of wheels is provided with a 55 suitable housing supported on a base 5 and connected with an air duct 6 through an inclined outlet 7, whereby the dust may be drawn away from the abrading wheels.

The housing consists of a hood 8 which 60 incloses the smaller of the two wheels 4 and is supported by suitable hinges 9 whereby it may be swung back to permit removal of said wheels. The larger wheel 3 is 65 inclosed between the side plates 10, 11 supported on suitable hinges 12, 13, whereby they may be swung aside to facilitate removal of said larger wheel. A hood 14 is arranged to cover the top of said larger wheel having side walls 15 which, with the 70 top wall, form an inclosing channel. Said hood 14 is rotatably mounted on the support 16 which in the present instance is in the form of a ventilating pipe or tube, the 75 ventilating feature forming no part of the present invention. An arm or partition 17 is also mounted on the tube 16, being arranged to turn therewith. Said arm is provided with an abutment or stop 18 at its outer end arranged to contact with the periphery of the polishing wheel 3, in case 80 said arm should be swung into contact therewith. The hood 14 is arranged to move with said arm 17 by means not shown herein, the extreme lower position of said hood being limited by the projection 21 thereon which engages the shoulder 22 on the main support.

The tube 16 has a gear sector 25 which is 85 engaged by the worm 26 on a spindle 27. Said spindle carries at one end a controller arm 28 constituting part of a rheostat 29 for controlling the speed of the motor. The other end carries a suitable hand wheel 30 whereby the operator may adjust the 90 rheostat. A plate 31 is mounted on the spindle 27 and is provided with peripheral 95 graduations which, in conjunction with a pointer 32, indicate to the operator the peripheral speed of polishing wheels of various diameters corresponding to a certain 100 adjustment of the rheostat.

When the operator places the polishing wheel or wheels of a certain diameter on the driving shaft, he adjusts the rheostat arm 105 to a certain predetermined position by reference to an instruction sheet and thereafter starts the motor by means of a push button

switch 33 or other switch which controls a motor starting device of any standard construction and not shown herein. The driving shaft thereby rotates at a speed which 5 will assure a proper and safe peripheral speed of the abrading wheel.

The pivoted arm 17 and the worm and gear connection therewith from the spindle 27 is to prevent the operator from making 10 improper adjustment of the rheostat arm. If the operator attempts to adjust the rheostat arm to such a position as would result in improperly speeding up the motor for a 15 polishing wheel of large diameter for example, the projection or stop 18 will come in contact with the stationary periphery of said wheel prior to the starting of the motor, obstructing further rotation of the hand wheel 30 and thereby calling the operator's 20 attention to the fact that the limit of adjustment has been reached. The operator thereupon gives the hand wheel a partial turn in the reverse direction to move the abutment 18 out of contact with the periphery of the polishing wheel, so that when the 25 motor starts there will be no unnecessary friction at this point.

Obviously this invention is capable of many variations and applications without departing from its spirit and scope, as 30 expressed in the appended claims.

What is claimed is:

1. In a device of the class described, a rotatable polishing wheel, a motor therefor, a 35 rheostat for said motor, a spindle carrying the rheostat arm, a worm on said spindle, a gear coöperating with the said worm, a shaft carrying said gear, and an arm on said shaft arranged to move in the plane of said 40 polishing wheel.

2. In a device of the class described, an electric motor, a shaft extending from both sides thereof, a polishing wheel on each side of said motor on said shaft, a supporting 45 member parallel to said shaft, a pair of arms on said member each arranged in the

plane of one of said polishing wheels, a rheostat adjacent to said motor and comprising a movable arm, a shaft on which said arm is carried, a handle on said shaft, 50 a worm also mounted on said shaft, and a gear mounted on said supporting member and coöperating with said worm.

3. In combination, an electric motor, a shaft extending from both sides thereof, 55 polishing wheels on said shaft on each side of said motor, a supporting member parallel to said shaft, a plurality of arms on said member in the plane of their respective polishing wheels, a rheostat for said motor, 60 means for manually adjusting said rheostat and simultaneously swinging said arms toward or away from said shaft whereby the radial positions of said arms with respect to said shaft and polishing wheels correspond 65 to a definite peripheral speed of the latter, and an indicator associated with said means to enable the operator to make the proper initial adjustment for the desired peripheral speed.

4. In a device of the class described, an electric motor, a polishing wheel on each side of said motor driven thereby, a supporting member parallel to the axis of rotation of said motor and polishing wheels, a pair 75 of arms on said member each arranged in the plane of one of said polishing wheels, a rheostat above said motor, a rotatable spindle extending forwardly from said rheostat, 80 a hand wheel on the forward end of said spindle, a dial adjacent to said hand wheel and mechanical connections between said spindle and said supporting member whereby said rheostat and said arms may be adjusted simultaneously from said hand wheel 85 to insure a peripheral speed of said wheels in accordance with the indications of said dial.

In witness whereof I hereunto subscribe my name this twenty-first day of October, 90 A. D. 1916.

HENRY FLEETWOOD ALBRIGHT.
